US0D1108456S

(12) **United States Design Patent** (10) **Patent No.:** **US D1,108,456 S**
(45) **Date of Patent:** **** Jan. 6, 2026**

(54) **DISPLAY SCREEN OR PORTION THEREOF WITH GRAPHICAL USER INTERFACE FOR A CRYOGENIC DEVICE**

(71) Applicant: **Pacira CryoTech, Inc.**, Tampa, FL (US)

(72) Inventors: **Jeffrey N. Gamelsky**, Palo Alto, CA (US); **Eric T. Johansson**, Dublin, CA (US); **Phillip Vallejo**, Newark, CA (US)

(73) Assignee: **Pacira CryoTech, Inc.**, Tampa, FL (US)

(**) Term: **15 Years**

(21) Appl. No.: **29/943,796**

(22) Filed: **May 23, 2024**

Related U.S. Application Data

(63) Continuation of application No. 29/780,337, filed on Apr. 23, 2021, now Pat. No. Des. 1,034,629.

CLAIM

The ornamental design for a display screen or portion thereof with graphical user interface for a cryogenic device as shown and described.

DESCRIPTION

The sole FIGURE is a front view of a display screen or portion thereof with graphical user interface for a cryogenic device, showing our new design.

The outermost dot-dash broken line depicts a display screen or portion thereof and forms no part of the claimed design. All remaining broken lines depict portions of the graphical user interface for cryogenic device that form no part of the claimed design.

1 Claim, 1 Drawing Sheet
